OSCILLATING SPRINKLER

Ellery L. Davis, Lincoln, Nebr.

Application August 23, 1937, Serial No. 160,532
Renewed October 12, 1939

4 Claims. (Cl. 299—71)

This invention relates to water sprinklers and more particularly to an automatic oscillating sprinkler, that is, a sprinkler having a discharge nozzle or nozzles which oscillates to spray or 5 cover a rectangular plot or surface to fully and evenly cover all parts of a lawn or the like.

An object of the invention is to provide such a device which is automatic in operation, the discharge nozzles being oscillated by the action of 10 the water under pressure which is admitted to the device for discharge therefrom.

Another object of the invention is to provide a sprinkler having a primary oscillating member and a secondary oscillating member mounted 15 thereon, the axes of oscillation of the two members being preferably parallel but necessarily not coincident.

Another object of the invention is to provide the primary oscillating member with an adjustable weight, the variance of which determines or 20 regulates the frequency of oscillation.

Other objects and advantages will appear when considered in connection with the accompanying drawing and description in which—

Fig. 1 shows a front elevation with the oscillating member or arm at the right hand extreme of its movement.

Fig. 2 is a side view, partly in section, showing the arm at dead center.

In the drawing in which like numerals indicate similar parts, 6 indicates a supporting base to which is clamped a fixed hollow spindle 7. A pipe coupling 8 surrounds the spindle 7, and is adapted to swing or pivot around the same. A primary 30 oscillating member comprising a hollow pipe or shaft 9 fits into the coupling 8 and communicates with a hose coupling 10.

Mounted for adjustable movement, up or down 40 on the pipe 9, is a weight 11 the function of which will be described later. Also mounted on the pipe 9 is an adjustable bracket 12 having arms 13 serving as limit stops and also serving to hold up the oscillator when not in action.

Mounted upon the upper end of the pipe 9 is a pipe coupling 14 through which extends a hollow arm 15, said arm having connected at its respective ends pipe unions 16, which as by nuts 17 and washers 18 connect the fan-shaped discharge nozzles 19 thereto. Openings 15a admit water from the pipe 9 to the arm 15. It will be noted that the nozzles 19 may be turned about their axes indicated by the line x—x to vary the width of the delivered spray.

Extending perpendicularly from the base 6 is

a stationary rod 20, which at its upper end has attached thereto, as by a clamp 21, a horizontal bar 22, said bar having pins 23 at its respective ends projecting outwardly therefrom in one direction. One of the unions 16 has a rod 24 extending downwardly from its base, said rod being confined within the space between the pins or rollers 23.

In operation, water enters under pressure through the hose connection 10, through the spindle 7, and up through the oscillating arm or pipe 9, thence through the longitudinal shaft or arm 15 and is then sprayed from the respective nozzles. The water under pressure passing in the manner described causes the pipe 9 by the back pressure or reaction to move to the left about its axis designated K—K, whereupon the rod 20 strikes or impinges the pin or roller 23 at the left hand end of the bar 22. This causes the nozzles to travel or swing to the left about the axis L—L, 20 which due to the force of the water issuing from the nozzles causes the oscillating pipe 9 to swing back to the right, whereupon the rod 20 strikes the pin 23 at the right hand end of the bar 22, causing the nozzles to swing to the right, which 25 causes the pipe 9 to again swing back to the left. Thus when water under pressure is issuing from the nozzles the pipe 9 is continually oscillated. The adjustable weight 11 affords a means of regulating the frequency of oscillation, the 30 oscillation being slower as the weight is raised. It will be noted that in ordinary operation the limit stops 13 do not strike the base member 6, for the apparatus reverses itself against the air only.

The device is adapted to spray a rectangular plot of ground and of course various types and 35 numbers of nozzles can be installed.

The hinged feet 50 may be used to level the 40 sprinkler on uneven ground if desired.

The drawing shows a vertical arrangement but the same principle could be applied to a horizontal or inclined arrangement.

I claim:

1. A sprinkler comprising a base, a hollow 45 spindle mounted thereon, a primary oscillating pipe pivoted to the spindle, an adjustable weight mounted on the pipe, a bracket mounted on the pipe arranged to strike the base and limit the oscillation of the pipe, a cross tube mounted in 50 a coupling at the upper end of the primary oscillating pipe, said cross tube terminating at its ends in unions to which are attached discharge nozzles forming secondary oscillating pipes so disposed that the reaction of the discharge from 55

the nozzles swings the primary pipe in one direction and the reversal of the nozzles swings the said pipe in the opposite direction, a rod rigidly attached to the base and a bracket attached to the upper end thereof, pins mounted on the ends of the bracket, and means extending from one of the unions to contact said pins and reverse the movement of the primary oscillating pipe.

2. A sprinkler comprising a base, a main oscillating pipe pivoted to the base, an upstanding rod rigid with the base, a cross bracket attached to the upper end of said rod, and having pins extending from both ends thereof, a secondary oscillating pipe pivoted on the upper end of the main oscillating pipe and provided with a nozzle so disposed that the reaction of the discharge from the nozzle swings the said main pipe, and a trip rod extending from the secondary pipe to contact with said pins respectively and thereby reverse the direction of swing of the oscillating pipes, the trip rod being of sufficient length to remain in contact with each of the pins respectively at the beginning and during the major part of the swing of the main oscillating pipe toward said pin, whereby the oscillation of the nozzle is effected gradually during each swing of the main oscillating pipe.

3. A sprinkler comprising an upright rod, an oscillating upright pipe beside the rod, an oscillating nozzle pivotally supported by and communicating with the upper end of said pipe, and

means actuated by the reaction of the discharge from said nozzle to automatically oscillate the pipe and also to automatically and gradually oscillate the nozzle with respect to said pipe, said means to gradually oscillate the nozzle including stops fixed to the rod, and a trip rod projecting from the nozzle between said stops and of sufficient length to have wiping contact with each of said stops at the beginning and during the major part of the swing of the upright pipe toward said stop.

4. A sprinkler comprising a base, a hollow spindle supported horizontally on the base and adapted for connection to a supply pipe, a primary oscillating pipe pivoted on the spindle to swing in a vertical plane above the base, a secondary oscillating pipe mounted in a bearing at the upper end of the primary pipe and provided with a nozzle swinging in a vertical plane parallel to the plane of oscillation of the primary pipe and so disposed that the reaction of the discharge from the nozzle swings the primary pipe in one direction and the reversal of the nozzle swings said pipe in the opposite direction, a support on the base, provided with opposite stops, and a trip rod projecting from the nozzle between said stops and of sufficient length to have wiping contact with each of said stops at the beginning and during the major part of the swing of the primary pipe toward said stop.
